(57) **CLAIM**

I claim the ornamental design for a plastic bottle, as shown and described.

DESCRIPTION

FIG. 1 is a front perspective view of a plastic bottle according to the present design;

FIG. 2 is a front elevational view of the plastic bottle of FIG. 1;

FIG. 3 is a rear elevational view of the plastic bottle of FIG. 1;

FIG. 4 is a right side elevational view of the plastic bottle of FIG. 1;

FIG. 5 is a left side elevational view of the plastic bottle of FIG. 1;

FIG. 6 is a top plan view of the plastic bottle of FIG. 1; and, FIG. 7 is a bottom view of the plastic bottle of FIG. 1.

The broken lines form no part of the design and are for illustrative purposes only.
